CLAIM

The ornamental design for a reel seat for fishing rod, as shown and described.

DESCRIPTION

FIG. 1 is a top, front and one side perspective view of a reel seat for fishing rod showing our new design;

FIG. 2 is a front elevational view thereof;

FIG. 3 is a rear elevational view thereof;

FIG. 4 is a side elevational view of the one side thereof;

FIG. 5 is a side elevational view of the opposite side thereof;

FIG. 6 is a top plan view thereof;

FIG. 7 is a bottom view thereof; and

FIG. 8 is a perspective view of a reel seat for fishing rod, the broken line showing of other parts of a fishing rod handle is for illustrative purposes only and form no part of claimed design.

*Fig. 1**Fig. 2**Fig. 3**Fig. 4**Fig. 5**Fig. 8**Fig. 6**Fig. 7*
